UNITED STATES PATENT OFFICE

161,592

DRINK DISPENSING UNIT

George Persak, Jr., Verona, N. J., assignor to
Lloyd E. Rabjohn, county of Los Angeles, Calif.

Application March 6, 1950, Serial No. 8,343

Term of patent 14 years

(Cl. D2—3)

To all whom it may concern:

Be it known that the undersigned, George Persak, Jr., a citizen of the United States, residing in Verona, State of New Jersey, has invented a new, original, and ornamental Design for a Drink Dispensing Unit, of which the following is a specification, reference being had to the accompanying drawing, forming a part thereof.

Fig. 1 is a side elevational view of a drink dispensing unit embodying my new design;

Fig. 2 is a rear elevational view thereof;

Fig. 3 is a plan view thereof; and

Fig. 4 is a front elevational view thereof.

I claim:

The ornamental design for a drink dispensing unit, substantially as shown.

GEORGE PERSAK, JR.
